MAGNETIZED TETHERED GOLF BALL AMUSEMENT DEVICE

Robert N. Nicodemus, Jr., and Rebecca Sue Nicodemus,
both of 5 E. Frederick St., Walkersville, Md. 21793

Continuation-in-part of design application Ser. No.
367,714, June 7, 1973. This application Oct. 18,
1973, Ser. No. 407,507

Term of patent 14 years

Int. Cl. D21—01
U.S. Cl. D34—15 P

FIG. 1

FIG. 2

FIG. 3

FIG. 1 shows in side elevation a magnetized tethered golf ball amusement device embodying our new design; FIG. 2 is a view from the left-hand side of FIG. 1; and

FIG. 3 is a top plan view.

The top surface of the base is shaded to indicate green. This application is a continuation-in-part of design application Ser. No. 367,714, filed June 7, 1973.

We claim:

The ornamental design for a magnetized tethered golf ball amusement device, as shown and described.
